MOLDED POULTRY NEST CUSHION

Glenn O. Bressler, 630 Franklin St., State College, Pa.,
and Arthur G. Perry, 203 Burncoat St., Worcester,
Mass.

Filed Nov. 16, 1959, Ser. No. 58,340

Term of patent 14 years

(Cl. D12—2)

FIG. 1

FIG. 2

FIG. 4

FIG. 3

FIG. 5

Figure 1 is a top plan view of a molded poultry nest cushion showing our new design;

Figure 2 is a side elevational view;

Figure 3 is an elevational view of one end;

Figure 4 is an elevational view of the other end; and

Figure 5 is a bottom perspective view.

The undisclosed side of the poultry nest cushion is substantially the same in appearance as the side shown.

We claim:

The ornamental design for a molded poultry nest cushion, as shown and described.
